RUNNING BOARD MAT FOR AUTOMOBILES

Harvey D. Geyer, Dayton, Ohio, assignor, by
mesne assignments, to General Motors Corpora-
tion, Detroit, Mich., a corporation of Dela-
ware

Application May 10, 1933, Serial No. 670,243

11 Claims. (Cl. 280—163)

This invention relates to automobile running boards and the like, and more particularly to means for securing the cover mat to the running board proper.

The object of this invention is to provide a simple and economically made yet very strong and efficient cover mat and improved means for fastening the same to a metal running board. An important feature of the invention is the ease and rapidity with which the cover mat may be originally properly secured in place upon the running board, or removed after a period of use and replaced by a new mat in case it becomes sufficiently worn to render its replacement desirable. In present day automobiles such mats often wear out or become unsightly so as to need replacement, but presently used means of attaching such mats render such replacement difficult and expensive due in great part to such attaching means being constantly exposed to mud, water, road tar, etc., and the consequent rust and corrosion thereupon. With the attaching means of this invention there are no threaded or other parts to rust tight and require cutting in two with a chisel to remove the old mat. The attaching lugs may be simply and quickly straightened out with hand pliers to re-register the shoulders on the lugs with their slots, after which the cover mat may be lifted from its running board.

The quick-attaching feature of the mat of this invention is also highly advantageous for the following reason. The automobiles may be shipped from the assembly plants to the dealers prior to assembling the cover mats upon the running boards and the dealer may quickly and simply attach these mats after the car is otherwise ready for showing. Thus the running boards will be kept new and clean without the need of the usual heavy paper or other covering used for temporarily keeping the running boards unmarred.

Another feature of this invention is the integral resilient rubber cushion buttons adjacent the attaching metal lugs on the under side of the sheet metal foundation of the cover mat, which cushion buttons are highly compressed when the cover mat is clamped down upon the running board proper by the attaching metal lugs, whereby the attachment is rendered tight and secure regardless of possible small inaccuracies in dimensions of the attachment metal parts.

Further objects and advantages of the present invention will be apparent from the following description, reference being had to the accom-

panying drawings, wherein a preferred embodiment of one form of the present invention is clearly shown.

In the drawings:

Fig. 1 is a plan view of a cover mat fixed in place upon an automobile running board, according to this invention. 5

Fig. 2 is a side elevation of Fig. 1.

Fig. 3 is a section taken on line 3—3 of Fig. 1.

Fig. 4 is a section taken on line 4—4 of Fig. 3 10 and shows the twisted metal lug in elevation.

Fig. 5 shows the attaching parts in juxtaposed relationship at the time of dropping the cover mat down upon the running board.

Fig. 6 is a bottom view of one of the attaching 15 devices on the cover mat, being taken on line 6—6 of Fig. 5.

Fig. 7 is a bottom view of one of the attaching devices on the board, being taken on line 7—7 of Fig. 5. 20

Figs. 8 to 11 show a modification.

Fig. 8 is a view similar to Fig. 4, but shows a modified form wherein the attaching metal lug is a separate piece from the metal foundation of the cover mat. 25

Fig. 9 is a view similar to the right end of Fig. 3 and shows the twisted metal lug in elevation.

Fig. 10 is a side elevation of the separate metal lug of Figs. 8 and 9 prior to its insertion in its slot 30 in the cover mat foundation.

Fig. 11 is an end elevation of Fig. 10.

Similar reference characters refer to similar parts throughout the several views.

Reference numeral 10 designates the pressed 35 sheet metal running board proper which may be of any suitable design. Figs. 1 and 2 show the outlines of a pressed metal board 10 which has a gradually upwardly sweeping front portion 11 which appears in effect as a continuation of the 40 curve of the front fender attached thereto. Board 10 also has a downwardly curved longitudinally extending outer edge portion 12, as clearly shown in Fig. 3, which extends the full length thereof. No claim is made herein for this 45 particular form of pressed metal running board per se. This invention comprises the combination of such a pressed metal board with a sheet metal reinforced cover mat therefor.

The cover mat of this invention is designated 50 as a whole by numeral 15, and comprises a quite flexible sheet metal foundation 16, preferably of steel, upon which is secured a non-metallic covering 17 of rubber or other suitable material which may be vulcanized, cemented, or otherwise suit- 55

ably fastened to the top surface of the metal foundation 16.

In the form illustrated in the drawings the cover 17 is of flexible rubber which is molded and vulcanized directly upon the steel foundation 16 and is thereby firmly surface bonded thereto during its vulcanization. The foundation is formed with upwardly turned margins, as shown at 18 in Fig. 3, which margins 18 are imbedded and entirely surrounded by the marginal beads 19 of flexible rubber. These marginal beads 19 are originally molded with an integral downwardly inclined somewhat flexible rubber lip 20 which projects below the bottom surface of the metal foundation 16. Then when the finished cover mat 15 is pressed down upon the upper surface of board 10, as will be described in greater detail hereinbelow, these rubber lips 20 will be forced into very tight contact with the metal board 10 and thereby provide a neat water-tight joint extending all around the periphery of the cover mat 15.

Figs. 3 to 6 illustrate a form of the invention wherein the sheet metal foundation 16 has a series of integral depending attaching lugs 25, which are cut out of the sheet metal 16 leaving a hole of the shape shown at 26 in Fig. 6 after the lug 25 is bent down at right angles. These lugs 25 each has an enlarged lower portion 27 and two opposed upwardly facing shoulders 28, as indicated by the shape of the hole 26 in Fig. 6. The sheet steel board 10 has a series of integral depressions or cups 30 pressed in the metal thereof, the centers of these cups 30 being punched out to form a round hole 31 with a narrow slot 32 extending thereacross. Each flat lug 25 is inserted straight down through the slot 32, as clearly shown in Fig. 5, and pressed down until the shoulders 28 thereon lie substantially flush with the bottom of the cup 30. The projecting head 27 of lug 25 may then be grasped with hand-pliers or other suitable tool and the lug 25 twisted at right angles to cause both its shoulders 28 to engage the under side of cup 30 and firmly clamp the cover mat 15 to the board 10 (see Fig. 4). Preferably the bottom of each cup 30 is formed with two small inclined cams 35 (see Figs. 5 and 7) so arranged that when lugs 25 are twisted the shoulders 28 will first engage these inclined cams 35, and as the twisting proceeds the shoulders 28 are cammed downwardly a small distance so that the clamping pressure between the steel foundation 16 and board 10 is increased. This camming action is highly advantageous for two reasons, namely: (1) A very tightly clamped relation between foundation 16 and board 10 is easily obtained thereby; and (2) great accuracy of dimensions of the lugs 25 and cups 30 is rendered unnecessary since the shoulders 28 on the lugs need not lie exactly flush with the under side of cups 30 when the twisting operation is begun.

Preferably a resilient cushion between foundation 16 and board 10 adjacent each lug 25 is provided by integral small rubber buttons 40 on the under side of foundation 16. Fig. 6 illustrates one arrangement of the location of these buttons 40. Buttons 40 may be conveniently molded integral with the rubber covering 17 by having small holes 41 in foundation 16 through which a neck 70 of rubber extends, as clearly shown in Figs. 3 to 5. These buttons 40 are highly compressed when the cover mat is clamped down in place upon board 10 as above described, and hence they serve to maintain the clamped relation tight by providing a certain amount of yieldability thereto.

Preferably a layer 21 of heavy tar paper or similar material is laid upon the top of board 10 before the cover mat 15 is placed thereupon. This layer 21 provides a filling for the space caused by the buttons 40 and also prevents any possible squeaking which might be caused by foundation 16 and board 10 rubbing together.

Figs. 8 to 11 illustrate a modified form of the invention wherein separate metal lugs 25' as shown in detail in Figs. 10 and 11, are provided instead of forming these attaching lugs integral with the foundation 16 as described above. These lugs 25' are first formed from sheet metal by stamping out the blanks and pressing to the form illustrated in Figs. 10 and 11. These lugs 25' are attached to the foundation 16' by inserting each lug snugly through an elongated slot therein until its flanges 50 rest thereupon, after which the projections 51 are staked or riveted over at the ends of the slot on the under side of foundation 16' (see Fig. 9). When the rubber covering 17 is later molded upon foundation 16' the flanges 50 are obviously completely concealed. In order to provide a proper thickness of rubber 17 above flanges 50, preferably foundation 16' is provided with a depression 49 therein equal in depth to the thickness of flanges 50 (see Figs. 8 and 9). The lugs 25' are inserted through the slots 32 in the cups 30 in board 10 and then twisted at right angles to firmly clamp the cover mat 15' to board 10 in the same manner as described in detail above. It will be noted that the round holes 31 are large enough to permit the turning therein in an easy spiral of the neck portion 52 of the lugs 25'. Thus there will be no severe tearing strains put upon these neck portions and they can be easily twisted to properly engage the shoulders 28' under the bottom edges of cups 30 on board 10, as described above.

It has been found preferable to vulcanize the rubber covering 17 to the steel foundation 16 or 16' while it is still in flat form to produce a flat cover mat as shown by the dotted line extension thereof in Fig. 3. This simplifies the form of the vulcanizing mold and thus reduces cost of manufacture. The flat cover mat may be then shaped in suitable dies approximately to the curved form shown in Figs. 2 and 3, the rubber covering being sufficiently flexible and resilient to permit such curving without cracking or otherwise harming the rubber. Since the finished unattached cover mat is still flexible to quite a degree it is not necessary that the curved form of the mat be shaped by the dies mentioned above to conform accurately to the curved form of the board 10 since it may be easily flexed or warped during its attachment to the board to provide the necessary fitting. This applies particularly to the upwardly sweeping curve given the forward portion of board 10 since the finished mat may be flexed to provide for this upward sweep without pre-forming.

While the form of embodiment of the present invention as herein disclosed, constitutes a preferred form, it is to be understood that other forms might be adopted, all coming within the scope of the claims which follow.

What is claimed is as follows:

1. In combination, a pressed metal running board for an automobile, a cover mat for said running board comprising a sheet metal foundation and a non-metallic covering bonded thereto, said metal foundation having a series of depending metal lugs each having two opposed upwardly facing shoulders thereon, said board having a

series of cams on its lower surface and a slot through each cam through which one of said depending lugs extends until its shoulders lie substantially flush with the adjacent under side of 5 said cam, each of said flat lugs being twisted to cause its shoulders to engage said cam and clamp said foundation down upon the upper face of said running board.

2. In combination, a pressed metal running 10 board for an automobile, a cover mat for said running board comprising a sheet metal foundation and a non-metallic covering bonded thereto, said foundation having a series of metal attachment lugs depending therefrom, each lug having 15 two opposed upwardly facing shoulders thereon, said board having a series of integral small depressions pressed therein, each depression having in its bottom a hole sufficiently large to receive and permit the turning therein of the neck 20 portion of said lugs and a slot across said hole sufficiently long to receive the full width of said lugs, said lugs being twisted after insertion through said slots to cause said shoulders to tightly engage the under side of said small depressions 25 so as to clamp said foundation upon said board.

3. In combination, a pressed metal running 30 board for an automobile, a cover mat for said running board comprising a sheet metal foundation and a non-metallic covering bonded thereto, said foundation having a series of metal attachment lugs depending therefrom, each lug having 35 two opposed upwardly facing shoulders thereon, said board having a series of integral small depressions pressed therein, each depression having a slot therein adapted to receive one of said lugs and having a cam surface on its under side adjacent said slot, said lugs being twisted after insertion through said slots to cause its shoulders to engage said cam surface and thereby clamp 40 said foundation upon said board.

4. In combination, a pressed metal plate, a cover mat therefor comprising a sheet metal foundation and a non-metallic covering bonded thereto, said foundation having a series of metal 45 lugs depending therefrom, each lug having an upwardly facing shoulder thereon, said plate having a series of cams on its lower surface and a hole adjacent each cam through which one of said depending lugs extends in such manner that 50 the shoulder thereon will engage said cam upon the relative lateral movement thereof, each of said lugs having a projecting portion which may be grasped with a suitable tool whereby the shoulder portion thereof can be moved laterally to engage the adjacent cam and thereby clamp said 55 foundation tightly against the pressed metal plate.

5. In combination, a pressed metal plate, a cover mat therefor comprising a sheet metal foundation and a non-metallic covering bonded thereto, said foundation having a series of metal 60 lugs depending therefrom, each lug having two opposed upwardly facing shoulders thereon, said plate having a series of cams on its lower surface and a slot adjacent each of said cams through 65 which one of said depending lugs extends in such manner that said shoulders will engage the cam upon a relative rotation of said shoulders, and means permitting the relative rotation of said shoulders to tightly clamp said foundation against 70 said plate.

6. In combination, a pressed metal plate, a cover mat therefor comprising a sheet metal foundation and a non-metallic covering bonded thereto, said foundation having a series of flat 75 metal lugs depending therefrom, each lug having

two upwardly facing shoulders thereon, said plate having a series of small depressions therein, each depression having in its bottom a hole of such size as to receive and permit the turning therein of the neck portion of said lugs and a slot across 5 said hole sufficiently long to receive the full width of said flat lugs, said lugs being twisted after insertion through said slots to cause said shoulders to tightly engage the under side of said depressions so as to clamp said foundation upon said 10 metal plate.

7. In combination, a base plate, a cover plate therefor, means for clamping said cover plate upon said base plate, said means comprising: a series of flat metal lugs projecting from said cover 15 plate each having two upwardly facing shoulders thereon, a registering series of small depressions pressed into said base plate, each depression having in its bottom a hole sufficiently large to receive and permit the turning therein of the 20 neck portion of said lugs and a slot across said hole sufficiently long to receive the full width of said flat lugs, said lugs being twisted after insertion through said slots to cause said shoulders to tightly engage the bottoms of said depressions 25 so as to clamp said cover plate against said base plate.

8. In combination, a base plate, a cover plate therefor, means for clamping said cover plate upon said base plate, said means comprising: a series of 30 distortable metal lugs depending from said cover plate, each lug having an upwardly facing shoulder thereon, said base plate having a series of cams on its lower face and a hole adjacent each cam through which one of said lugs projects, each of 35 said lugs being twisted by distortion of the metal thereof to cause the shoulder thereon to engage the adjacent cam and thereby clamp said cover plate against said base plate.

9. In an automobile having a chassis frame, in 40 combination, a pressed metal running board having a curved step surface and extending alongside the chassis frame and fixed thereto, a flexible cover mat for said curved step surface comprising a flexible sheet metal foundation and a flexible 45 rubber covering bonded thereto, said foundation having a series of spaced depressions pressed in the metal thereof, each depression having a narrow slot therein, and a separate metal attachment lug for each depression, said lugs each having 50 an upper flange lying within the depression and covered by said rubber covering and a flat depending portion projecting snugly through the slot therein, said metal board having a series of holes 55 therein through which said flat depending portions project and means for securing the projecting ends of said flat depending portions against withdrawal from said holes.

10. In an automobile having a chassis frame, in 60 combination, a pressed metal running board having a curved step surface and extending alongside the chassis frame and fixed thereto, a flexible cover mat for said curved step surface comprising a flexible sheet metal foundation and a flexible rubber covering bonded thereto, said foundation 65 having a series of spaced depressions pressed in the metal thereof, each depression having a narrow slot therein, and a separate metal attachment lug for each depression, said lugs each having an upper flange lying within the depression and 70 covered by said rubber covering and a flat depending portion projecting snugly through the slot therein, said metal board having a series of holes therein through which said flat depending portions project, the projecting ends of said flat de- 75

pending portions being deformed after insertion through said holes to clamp said flexible foundation to said board.

- 5 11. In an automobile having a chassis frame, in combination, a pressed metal running board having a curved step surface and extending alongside the chassis frame and fixed thereto, a flexible cover mat for said curved step surface comprising a flexible sheet metal foundation and a flexible 10 rubber covering bonded thereto, said foundation having a series of spaced depressions pressed in the metal thereof, each depression having a narrow slot therein, and a separate metal attachment

lug for each depression, said lugs each having an upper flange lying within the depression and covered by said rubber covering and a flat depending portion projecting snugly through the slot therein, said metal board having a series of pockets pressed in the metal thereof into which said foundation depressions extend, each pocket having a hole therein through which said flat depending portions project, and means for securing the projecting ends of said depending portions 10 against upward withdrawal from said holes. 5

HARVEY D. GEYER.
